METHOD OF AND APPARATUS FOR PERFORMING LOOPING ON A MULTINEEDLE SEAM COVERING SEWING MACHINE

Fritz Ebert, Oberndorf-on-the-Neckar, Germany, assignor to Mauser-Werke A.-G., Oberndorf-on-the-Neckar, Germany, a joint-stock company of Germany

Application August 4, 1936, Serial No. 94,246
In Germany February 20, 1935

14 Claims. (Cl. 112—165)

This invention relates to a method and also an apparatus enabling articles or pieces of work to be sewn continuously in such fashion on a multi-needle seam covering sewing machine that looping is also performed between the pieces of work, i.e., at points where there is no material, so that a proper seam is produced immediately upon the introduction of the second or following piece of work.

10 The purpose of the invention is to provide means for adapting the length of the needle thread drawn at any time, to the thickness of the material, so that also in embroidering without material the correct length of the thread is obtained.

15 The actual stitches of the overlapping seam are formed by the looper thread, whereas the needle threads for the purpose of connecting the 20 stitches correctly with each other and hence loops must be formed by the needle threads into which the looper can enter.

25 For this reason the needle threads upon downward movement of the needles are caught so that sufficient length of thread is present to form these loops when the catching is stopped.

If this place of catching for the needle threads is fixed then always the same length of thread will be drawn without consideration whether the 30 material is thick or thin or whether any material is present on the stitch plate and below the pressure foot. In other words it is as if the length of the thread were in reverse proportion to the requirements, because with thick material, that 35 is when more thread must be drawn because a greater part of the thread length lies inside the material thickness than in the case of thinner material, since the thread length is always the same, the loops for the looper will be smaller.

40 Since however, the loop must have a minimum size, this minimum size must be determined by the thickest material which is to be sewn and this length in the case 45 of thinner material or when no material is present is much too great. Hence arises the possibility that the seam will not have sufficient firmness because the thread is not drawn sufficiently tight. From this consideration it is seen 50 that the length of thread must not always remain the same but that the catching of the needle threads must be effected in such a manner that the length of thread shall correspond to the actual conditions so that always independent of whether thick or thin material or even

no material is under the pressure foot, the loop which the looper has to enter must have the correct size.

For this reason it is proposed according to the invention to make the catching place for the 5 needle threads variable in such a manner that in the case of thick material correspondently more thread is drawn than with thin material or when no material is present, and this constitutes the main feature of the invention.

According to the invention a finger is provided attached to the pressure foot rod and which thus effects upward and downward movement corresponding to the thickness of the material present. Therefore, corresponding to the thickness 15 of the material the finger determining the place of catching will lie higher or lower and will draw off the necessary thread length required for the desired size of loop. The finger is also pivotable about the pressure foot rod in a horizontal plane 20 in order that, at the beginning of the down stroke of the needles it can be swung in close behind these in the path of the needle threads, and upon arrival of the needles in the lowest position, when the looper again moves forward, will again move 25 back in order that the needle threads may slide off the looper and after falling downwards can form loops. In order finally to take care of the different needle and thread thicknesses there is 30 provided a further adjustment by means of which the finger can be approached more or less closely to the plane of the needle whereby no change is made in its other functioning. A feature of the invention also consists in the finger moving in 35 a transverse slot in the pressure foot whereby the finger not only receives an exact guiding but is also given a support when the overlying thread is drawn downwards. The finger may thus be made comparatively thin.

40 The method according to the invention is illustrated in a possible form of embodiment in the accompanying drawings in conjunction with a sewing machine of the supporting arm type. It will be understood, however, that the invention 45 is not restricted to this form of embodiment or to sewing machines merely of this kind.

Fig. 1 is a perspective view of the sewing machine, in which only those parts have been shown which directly pertain to the invention.

Fig. 2 is a plan view of the looping device in which the finger has been advanced up to the middle needle.

Fig. 3 is an elevational view in vertical section.

Figs. 4 and 5 are similar elevational views in 55

vertical section before and after the downward movement of the needles.

Figs. 6 and 7 are a rear view and sectional plan view respectively of the drive.

5 Figs. 8 to 10 illustrate progressively the formation of the seam.

The sewing machine, in conjunction with which the method according to the application will be described, is assumed to be of the supporting arm type. The sewing or stitching mechanism is of the usual kind, this also applying to the drive for the elements producing the seam. In the particular form of embodiment shown these elements comprise three needles 1, the looper 3 operating in the arm 2 and the presser 4. The needles 1 guide the threads 5 and the looper 3 guides the thread 6.

The method according to the invention consists in the fact that the needle threads 5 upon the downward movement of the needles 1 are prevented from being drawn and also prevent the looper 3 from entering the needle thread loops. In the embodiment according to the invention, this is effected by means of a finger 7, which is 20 preferably comparatively thin and curved and may be resilient in itself, but may also be of other form. This finger 7 moves prior to the downward movement of the needles 1 behind the latter or between their path of movement and the needle threads 5, as shown more particularly in Figs. 4 and 8. Upon the downward movement of the needles 1, the needle threads 5 are then held by the finger 7, as shown in Figs. 5 and 9, so that the looper 3 is able to enter the needle thread loops 35 8, as shown in Fig. 10.

According to the invention a finger 7 is provided attached to the pressure foot rod 9 and which thus effects upward and downward movement corresponding to the thickness of the material present. Therefore, corresponding to the thickness of the material the finger 7 determining the place of catching will lie higher or lower and will draw off the necessary thread length required for the desired size of loop. 7 dependent on the thickness of the article or piece of work, the shorter amount of thread being drawn through when sewing is performed in the absence of material.

8 Having now particularly described and ascertained the nature of my said invention, and in what manner the same is to be performed, I declare that what I claim is:

9 1. In a seam covering sewing machine, a plurality of needles, a presser foot, a fixed needle plate tongue constituting the point of formation of the loops, and a finger movable together with the said presser foot for firmly holding the needle threads, upon each downward movement of the said needles, at a point which is variable in relation to the point of formation of the covering seam. 10

10 2. In a seam covering sewing machine, a plurality of needles, a presser foot, a fixed needle plate tongue constituting the point of formation of the loops, and a finger adapted to rock about a vertical axis and movable together with the said presser foot for firmly holding the needle threads, upon each downward movement of the said needles, at a point which is variable in relation to the point of formation of the covering seam. 15

15 3. In a seam covering sewing machine, a plurality of needles, a presser foot, a fixed needle plate tongue constituting the point of formation of the loops, and a finger adapted to rock about the rod 20 of the said presser foot and connected therewith in positive fashion for firmly holding the needle threads, upon each downward movement of the said needles, at a point which is variable in relation to the point of formation of the covering seam. 25

20 4. In a seam covering sewing machine, a plurality of needles, a presser foot, a fixed needle plate tongue constituting the point of formation of the loops, and a finger adapted to be lifted in common 25 with the said presser foot for firmly holding the needle threads, upon each downward movement of the said needles, at a point which is variable in relation to the point of formation of the covering seam. 30

30 5. In a seam covering sewing machine, a plurality of needles, a presser foot, a fixed needle plate tongue constituting the point of formation of the loops, and a finger movable together with the said presser foot for firmly holding the needle threads, upon each downward movement of the said needles, at a point which is variable in relation to the point of formation of the covering seam, the path of movement of the said finger 35 passing through the said presser foot. 40

35 6. In a seam covering sewing machine, a plurality of needles, a presser foot, a fixed needle plate tongue constituting the point of formation of the loops, a finger for firmly holding the needle threads, upon each downward movement of the said needles, at a point which is variable in relation to the point of formation of the covering seam, and means for adjusting the plane of the said finger in relation to the said needles. 45

45 7. In a seam covering sewing machine, a plurality of needles, a finger for firmly holding the needle threads, upon each downward movement of the said needles, at a point which is variable in relation to the point of formation of the covering seam, and means for displacing the said finger vertically comprising a finger holder having an opening therein adapted to receive a shaft of the said finger and serving for vertical adjustment of the finger. 50

5 8. In a seam covering sewing machine, a plurality of needles, a presser foot, a fixed needle plate tongue constituting the point of formation of the loops, a looper, a finger rocked by the drive of the said looper for firmly holding the needle threads, upon each downward movement of the said needles, at a point which is variable in relation to the point of formation of the covering seam, and an adjustment device for controlling the extent of the rocking movement. 10

10 9. In a seam covering sewing machine, a plurality of needles, a presser foot, a fixed needle plate tongue constituting the point of formation of the loops, a looper, a transverse shaft driving the said looper, and a finger rocked by the said transverse shaft for firmly holding the needle threads, upon the downward movement of the said needles, at a point which is variable in relation to the point of formation of the covering seam. 15

15 10. In a seam covering sewing machine, a plurality of needles, a presser foot, a fixed needle plate tongue constituting the point of formation of the loops, a looper, a transverse shaft driving the said looper, a finger for firmly holding the needle threads, upon each downward movement of the said needles, at a point which is variable in relation to the point of formation of the covering seam, and an arm on the said transverse shaft for actuating the said finger. 20

20 11. In a seam covering sewing machine, a plurality of needles, a presser foot, a fixed needle plate tongue constituting the point of formation of the loops, a looper, a finger rocked by the drive of the said looper for firmly holding the needle threads, upon each downward movement of the said needles, at a point which is variable in relation to the point of formation of the covering seam, and means connecting the said looper drive with the said finger, the transmission ratio between the said looper drive and the said finger 40 being variable by varying the point of engagement of the said connecting means. 35

35 12. In a seam covering sewing machine, a plurality of needles, a presser foot, a fixed needle plate tongue constituting the point of formation of the loops, a looper, a finger rocked by the drive of the said looper for firmly holding the needle threads, upon each downward movement of the said needles, at a point which is variable in relation to the point of formation of the covering seam, means for connecting the said looper drive with the said finger, and means for adjusting the said connecting means. 45

45 13. A method of performing looping on a multi-needle seam covering sewing machine, comprising the step of firmly holding the needle threads, upon each downward movement of the needles, at a point which is variable in relation to the point of formation of the covering seam and lifting the needle threads to perform the looping in 50 dependence upon the thickness of the material and during the upward movement of the needles the needle threads being freed. 60

55 14. In a seam covering sewing machine, a plurality of needles, a presser foot, and a finger movable together with the said presser foot for firmly holding the needle threads, upon each downward movement of the said needles, at a point which is variable in relation to the point of formation of the covering seam. 65
